G. J. KROMER

GARMENT FASTENER

Filed May 24, 1928

FIG. 1.

FIG. 2.

FIG. 3.

INVENTOR.

GEORGE J. KROMER

BY

Ralph L. Brown

ATTORNEY.

UNITED STATES PATENT OFFICE.

GEORGE J. KROMER, OF MILWAUKEE, WISCONSIN.

GARMENT FASTENER.

Application filed May 24, 1928. Serial No. 280,357.

This invention relates primarily to garment fasteners, although it will serve adequately as a securing means for other articles.

The primary object of this invention is to provide an improved garment fastener which will serve as a superior substitute for buttons.

A more specific object is the provision of a fastening device which will stand hard usage and frequent laundering without impairing its utility.

Numerous attempts have heretofore been made to provide a fastening device which would eliminate the use of buttons, which have continuously proven unsatisfactory due to loss and breakage, especially in instances where garments require laundering. As instances of these attempts, metallic fastening devices, such as snappers, and hooks and eyes have been used. The use of these devices have only a limited scope and they too have proven unsatisfactory as they are frequently misshapen in laundering, and their utility thus impaired.

A real need still persists for a fastening device which will overcome all of the defects of loss, breakage, and deformation resulting from the use of buttons, metallic fasteners, etc.

Other more specific objects and advantages will appear from the following description of an illustrative embodiment of the present invention.

In the drawings:

Figure 1 is a view in elevation of a garment fastener, constructed in accordance with the present invention, showing the same in separated or open condition.

Fig. 2 is a similar view showing the fastener in assembled or closed condition.

Fig. 3 is a sectional view taken upon the line 3—3 of Figure 2.

The garment fastener selected for illustration is shown applied to the adjacent flaps or overlapping portions 10 and 10' of a garment. Adjacent one edge 11 of the portion 10, one end 12 of a pliable tongue 13, made of suitable woven material, is applied by means of stitching 14 or other suitable means. An elongated head 16 preferably made of felt or other flexible material, which has been chemically treated, or sized, to stiffen the same, is applied by stitching 18 intermediate its ends to the free end 17 of the tongue 13, and forms, in effect, an extension of said

tongue. A spacer element 19 is preferably interposed between the head and tongue. Adjacent the edge 20 of the other portion 10', a slot 21 is cut extending transversely of the head. An element 22 is preferably applied to the under side of the garment surrounding the slot 21 and secured to the same by means of stitching 23, to serve as a reinforcing element for the slot.

To fasten the two portions of the garment 10 and 10' as shown in Figure 1, the head 16 carried by the tongue 13 on portion 10 is threaded through the slot 21 in the other portion 10'. It will be noted that the head 16 is considerably longer than the width of the slot 21 and therefore the head 16 will cover the slot and extend both forwardly and rearwardly thereof. An attempt to separate the two portions of the garment will show that they are locked together and that the head 16 cannot be removed from the slot 21 without first pulling the same forwardly and threading the rear end of the head 16 through the slot. This operation is an unnatural one and will not be accomplished without manual manipulations. Hence the fastener will remain in this locked position until the individual sees fit to unfasten the same. When the garment has become soiled and laundering is necessary, the same can be laundered in the usual manner with positive assurance that the fastening device will not be broken or detached from the garment nor will it lose any of its aptitude for the duty it performs. As the chemical treatment of the head 16 is of such a nature as to be impervious to water, the stiffness will persist in spite of frequent laundering. The remaining portions of the fastener are of such a nature that laundering will in no way harm them.

The reinforcing element 22 may be omitted without material defect, by merely finishing the hole with a button hole stitch, and the spacer element 19 which is shown as a separate element may as readily be formed by turning the end 17 back upon itself and stitching the head 16 thereto.

The foregoing specification described a fastening device which provides a superior substitute for buttons or metallic fastening devices, and is of such a nature as to permit frequent laundering and hard usage without impairing its effectiveness. It will also be noted that the device may be so constructed as to afford not only a fastening means for

the garment but also has decorative qualities. In the embodiment shown in the accompanying drawings the tongue 13 has been permitted to extend beyond the edge 20 of 5 the garment for illustrative purposes only, and it will readily be seen that the same might well reside underneath this portion of the garment to hide the same from view, should it be so desired.

10. Various changes may be made in the embodiment of the invention hereinabove specifically described without departing from or sacrificing any of the advantages of the invention as defined in the appended claims.

15. I claim:—

1. In a garment or the like having separable portions, the combination of a non-metallic fastener therefor comprising a flexible tongue attached at one end to one of said portions, a flexible elongated head applied lengthwise on said tongue, said head having a rearwardly extending end free from said tongue, and a head receiving opening on said other portion for coaction with the rear end 25 of said head to lock said portions against accidental separation.

2. In a garment or the like having separable portions, the combination of a non-metallic fastener therefor comprising a flexible tongue attached at one end to one of said portions, an elongated fabric head applied intermediate its ends to the free end of said tongue, said head extending lengthwise of said tongue with its rear end free therefrom 35 and a head receiving opening on said other portion for coaction with the rear end of said head to lock said portions against accidental separation.

3. In a garment or the like having separable portions, the combination of a fastener therefor comprising a flexible tongue at-

tached at one end to one of said portions, an elongated head applied lengthwise on said tongue, a spacer element interposed between said head and said tongue, said head having an end extending rearwardly of said spacer element, and a head receiving opening on said other portion for coaction with the rear end of said head to lock said portions against accidental separation. 45 50

4. In a garment or the like having separable portions, the combination of a fastener therefor comprising a flexible tongue attached at one end to one of said portions, an elongated head applied to the free end of said tongue to form in effect an extension thereon, a spacer element interposed between said head and said tongue, said head having an end extending rearwardly of said spacer element, and said other portion having a slot 55 60 extending transversely of the head to receive said head to lock said portions against accidental separation.

5. In a garment or the like having separable portions, the combination of a fastener therefor comprising a flexible tongue attached at one end to one of said portions, an elongated head applied to the free end of said tongue to form in effect an extension thereon, a spacer element interposed between said head and said tongue, said head having an end extending rearwardly of said spacer element, said other portions having a slot 70 75 extending transversely of the head to receive said head to lock said portions against accidental separation, and an element surrounding the slot and attached to said other portion to serve as a re-enforcement for the slot.

In witness whereof, I hereunto subscribe my name this 22nd day of May, 1928.

GEORGE J. KROMER.
